(57) **CLAIM**

The ornamental design for a trigger point massage cane as shown and described.

DESCRIPTION

FIG. 1 is a front, right and top perspective view of a trigger point massage cane, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the trigger point massage cane in a second position of use, showing the lower part of the trigger point massage cane being twisted to another side; and,

FIG. 10 is another front, right and top perspective view of the trigger point massage cane in a third position of use, showing the middle part and the lower part of the trigger point massage cane being twisted to another side.

1 Claim, 10 Drawing Sheets
